UNITED STATES PATENT OFFICE

JOHN F. PETERS, OF EDGEWOOD, PENNSYLVANIA, ASSIGNOR TO WESTINGHOUSE ELECTRIC & MANUFACTURING COMPANY, A CORPORATION OF PENNSYLVANIA

SURGE RECORDER

Application filed July 31, 1924, Serial No. 729,426. Renewed March 6, 1929.

My invention relates to electrical instruments and particularly to instruments for recording surges of current or voltage.

This invention is an improvement on the 5 surge recorder disclosed in my Patent No. 1,649,180, granted November 15, 1927, on application Serial No. 680,569, filed December 13, 1923.

One object of my invention is to provide 10 an instrument for recording periodic or recurrent surges.

Another object of my invention is to provide a surge-recording instrument of the electrostatic type in which the record is so 15 modified that the shape of the figure will indicate the time-characteristics of the surge.

A further object of my invention is to provide a surge recorder having a movable recording element and shielding means for limiting the size of the record in the direction of motion of the recording element, so that a record of the duration and periodic character 20 of the surge may be obtained.

For a better understanding of my invention, reference may be had to the accompanying drawings wherein,

Figure 1 is a diagrammatic view of a surge recorder constructed in accordance with the invention; and

Fig. 2 is a view of the record produced by the recorder when subjected to a surge.

Referring to Fig. 1, a surge recorder 1 is connected to a line 2 that is subjected to abnormal surges of voltage. The recorder com-

35 prises an electrode 3 in engagement with a moving sensitized recording element 4, that may be a flexible photographic film coated with emulsion and similar to that used in ordinary photographic work. The film is

40 driven by a suitable motor or clock-work mechanism 5 connected to the film reels 6 and 7. A belt 8 connects the reels 6 and 7. The film 4 is supported under the electrode 3 by a

45 rotating grounded cylinder or drum 9, the film being insulated from the drum by insulation 10. Flat metallic grounded shields 11 are positioned across the film 4 adjacent to the electrode 3. These shields are insulated in

50 any suitable manner from the electrode 3,

for example, by a layer of insulating material 11'.

Upon the occurrence of a surge in the line 2 that produces potentials in excess of 3000 volts between the electrode 3 and the drum 9, a figure is produced upon the sensitized film 4. The size and appearance of this figure is an indication of the intensity, polarity and duration of the surge in the line. Without the shields 11, this figure would be substantially circular in shape but, due to these transverse shields at the same potential as the drum 9, the figure is restricted in the direction of motion of the film and therefore the dimension of the record in this direction 55 is a measure of the duration of the surge.

As shown in Fig. 2, instead of being circular, the length of the figure in the direction of motion of the film is determined by the speed of travel of the film and the duration 60 of the surge. The transverse dimensions of the figure, however, provide an indication of the instantaneous values of the surge potentials. When there are recurrent surges or when the voltage disturbance is periodic during its existence, a succession of figures is 65 produced showing the general change in character of the surge. Since the minimum time required to effect a record upon the film has been determined to be in the neighborhood of 70 a millionth of a second, it is evident that changes in voltage of any rate that is of practical interest or importance may be recorded and measured.

The film 4 may be driven at any desired 75 rate. Thus, if it is only connected to a conductor for a short time during a surge thereon instead of being permanently connected, the film may be arranged to travel at a high speed during such connection, and it will 80 then be possible to record periodic surges of extremely high frequencies.

It will be apparent that I have provided a recording device that is adapted to record the characteristics of a fluctuating electrical disturbance even though it is exceedingly brief duration. Since there are no moving parts having mechanical inertia that are concerned with producing the record, it is capable of application in measuring surges and other 95 100

phenomena that cannot be recorded by the usual measuring instruments.

I do not consider that my invention is limited to the precise form shown and described and accordingly I do not wish to be limited in scope except by the appended claims.

I claim as my invention:

1. An instrument comprising a movable sensitized recording element, means for moving said element, and a shielded electrode adjacent to said element for cooperation therewith, and grounded metallic members for shielding the electrode to limit the area of the element affected thereby.

15. 2. An instrument comprising a sensitized recording element, means for moving the same, and an electrode in engagement therewith, said electrode being shielded laterally with respect to the direction of movement of said element by grounded metallic members insulated from said electrode.

20. 3. An instrument comprising a sensitized recording element, an electrode cooperating therewith, and a grounded member adjacent said electrode to modify the record produced on said element.

25. 4. An instrument comprising a conducting member presenting a convex surface, a sensitized recording element supported thereby but insulated therefrom, and a shielded electrode engaging said element.

30. 5. An instrument comprising a grounded member, recording means thereon, insulation between said member and said means and a second grounded member for modifying the record produced by said means.

35. 6. An instrument comprising a sensitized recording element, an electrode in engagement therewith, and means adjacent to said electrode for deforming the figure normally produced on said element.

40. 7. An instrument comprising a rotating drum, a sensitized recording element carried thereby, an electrode in engagement with said element and a shield adjacent said electrode.

45. 8. An instrument comprising a grounded rotatable metallic drum, a flexible sensitized element on said drum, an electrode in engagement with said element and a transverse shield adjacent the electrode.

50. 9. An instrument comprising an electrode, a flexible sensitized element engaged thereby and cooperating therewith and shielding means for modifying the record produced by said electrode on said recording element.

55. 10. The combination for use with a line subject to abnormal surges, comprising an electrode, a flexible sensitized element engaged thereby and cooperating therewith and shielding means for modifying the record produced by said electrode on said recording element.

60. 11. An instrument comprising a sensitized recording element, an electrode in engage-

ment therewith, and an electrostatic shield adjacent to said electrode.

65. 12. An instrument comprising an electrode, a sensitized element engaged thereby and means cooperating with the electrode to modify its effect on said element.

70. 13. An instrument comprising an electrode, a sensitized element engaged thereby and cooperating therewith and cooperating means for limiting the record produced on the element by the electrode within predetermined confines.

75. 14. An instrument comprising an electrode, a sensitized element engaged thereby and cooperating therewith and movable relative thereto, and cooperating means for limiting a record produced on the element by the electrode in the direction of relative movement of the element.

80. 15. An instrument comprising a sensitized element, an electrode engaging said element normally adapted to effect a record of substantially circular area on said element and cooperating means for limiting the formation of said record on the element to at least one elongated figure equal to the diameter of said circular area.

85. 16. An instrument comprising an electrode, a grounded metal platen, a sensitized element between the electrode and the platen, and a grounded element on the electrode side of the sensitized element for affecting the record produced by the electrode on the sensitized element.

90. In testimony whereof, I have hereunto subscribed my name this 29th day of July, 1924.
